UNITED STATES PATENT OFFICE.

PATRICK B. DELANY, OF NEW YORK, N. Y., ASSIGNOR TO THE STANDARD ELECTRIC MANUFACTURING COMPANY, OF SAME PLACE.

ELECTRICAL SYNCHRONOUS MOVEMENT.

SPECIFICATION forming part of Letters Patent No. 286,277, dated October 9, 1883.

Application filed April 12, 1883. (No model.)

To all whom it may concern:

Be it known that I, PATRICK B. DELANY, of the city, county, and State of New York, have invented certain new and useful Improvements in Synchronous Movements, of which the following is a specification.

The object of my invention is to provide means by which electrically-connected apparatus can be caused to move simultaneously in the same time. Under the organization which I will now describe, momentary variations within certain limits, either of acceleration or of retardation, are promptly corrected by retarding or accelerating electrical impulses; and such variations, being constantly corrected whenever they occur, do not constitute imperfections in the operation of my invention. Various devices have heretofore been employed for governing such movements, and among others tuned forks and other vibrators; and in several applications for Letters Patent filed simultaneously herewith, I have described and illustrated systems of operation in which electrically-controlled vibrators are relied upon to maintain the synchronous movement of the different apparatus. Under the organization herein disclosed, however, I dispense with the use of vibrators of any description, and employ a continuously-acting, non-vibratory, automatic circuit-breaker, in the interrupted circuit of which the motor-magnet which drives the electrically driven or rotated apparatus at the different stations is placed.

In the accompanying drawings, Figure 1 is a plan view, partly broken away, illustrating the transmission-instrument; Fig. 2, a side elevation of the same with the contact-tongues broken off. Fig. 3 is a diagrammatic plan view illustrating two stations connected by a main line, and Fig. 4 is a similar view of a slightly-modified organization.

Referring to Figs. 1 and 2, the apparatus is mounted upon a base-board, A, in which a vertical rotating shaft, B, has its lower bearing, the upper bearing of the shaft being in the bridge piece or strap B'. A stationary table, C, on the face of which a series of insulated contacts is arranged, is placed concentrically around the rotating shaft D, and a trailing finger or circuit-completer, e, held adjustably in the outer end of a radial arm, b',

projecting from the insulated hub a' on the rotating shaft, sweeps over the table of contacts. A spring contact-tongue, a, mounted in a suitable post or support, a', bears upon the hub a', and is electrically connected with the main line. As the trailing finger therefore moves over the circular table of contacts, the main line will, through the tongue a and trailing finger e, be successively momentarily placed in communication with each of the insulated contacts on the stationary table. Just above the hub a' is an armature-disk, D, fast on the vertical shaft B. This disk is provided with armature-teeth d on its periphery, which revolve in close proximity to the poles of the magnets E E and F F, as is presently described. On the upper face of the armature-disk D is a cylindrical case, d', filled with mercury to render the motion of the disk uniform. A make-and-break wheel or circuit-interrupter, g, is secured on the vertical rotating shaft B, just above the cylindrical mercury-case d'. A spring contact-tongue, i, bears upon the periphery of this wheel, and the electrical connection is alternately broken and completed through the wheel, the hub l, and the spring g contact-finger g', which bears upon the hub. The spring i is electrically connected with one end of a local battery-circuit, in which the motor-magnet F F, which actuates the rotary disk D, is placed, and the contact-tongue g is connected with the other end of the circuit. In order to prevent sparks between the break-wheel and the tongue i, a shunt containing a resistance, R, is thrown around them, as in Fig. 3. An impulse of rotation having been imparted to the vertical shaft, the local or motor circuit will be automatically made and broken through the break-wheel g, and the magnet F F magnetized and demagnetized; and when the speed of rotation corresponds with the makes and breaks in the circuit, the armature-teeth d will be alternately attracted and released by the poles of the motor-magnet F F, and the disk continuously rotated, as is well understood. This magnet is mounted upon a sliding support or standard, F', which is adjusted to and from the teeth d of the armature-disk by means of a suitable screw, F''. The magnet E E is for the purpose of regulating the speed of rotation, and acts upon

the armature-teeth *d* whenever correcting impulses of electricity are transmitted over the line, as hereinafter described. This magnet is mounted upon a sliding support, *E'*, which 5 is adjusted toward and from the armature-teeth *d* by means of a thumb-screw, *e*, mounted in a vertical ear or bracket on the base-piece *E'*. This base-piece is adjustable on the bed-piece *A* of the instrument by means of curved 10 slots and set-screws *e'*, so that it may be adjusted sidewise concentrically with the armature-disk *D*. By this adjustment the poles of the magnets *E* can be brought into the proper relation to the teeth on the rotating armature-disk, so that the correcting impulses of 15 electricity will act properly upon the teeth of the rotating armature-disk to regulate its movement, as hereinafter described.

In Figs. 3 and 4 the parts are, for the purposes of illustration, represented diagrammatically, and the stationary table of contacts is shown as placed above the rotating armature-disk and interposed between that disk and the trailing finger *c*.

25 The device of employing a mercury-case for evening the speed of rotation of the armature-disk is not new with me, and forms no part of the present invention; nor is it necessary to the operation of my invention, though I prefer to employ it. The manner of driving the armature-disk—that is, by means of a motor-magnet placed in a circuit which is automatically made and broken—is also old, as is well understood. In organizations, however, like 30 those herein illustrated, the motor-circuit has been made and broken by the action of an automatic vibrator, and not by means of a rotary circuit-breaker, nor by a circuit-breaker operated directly by the rotation of the disk itself.

Two stations, *X* and *Y*, are illustrated in the drawings, and at each station I have shown a table of contacts on which sixty insulated contacts are placed. These contacts are divided 45 into groups or series of ten each, making six groups, and two of the contacts in each group—those numbered 9 and 10—are devoted to maintaining the synchronous movement of the apparatus, as will be described. The remaining 50 eight contacts in each series may be connected in any desired way with electrical apparatus at each of the stations.

It will be obvious that if the trailing fingers *c* rest on corresponding contacts at the two stations the circuit between them will be complete. Any apparatus, therefore, connected in proper electric circuit with such corresponding contacts at each station will receive an electrical impulse once for each revolution of 60 the trailing finger. If several instruments at each station—say four—are connected up in independent circuit with two of the contacts of each of the six series, it will be obvious that the circuit over the main line will be completed through the corresponding instruments at each station twelve times in each revolution of the trailing fingers. If the apparatus

is made to rotate, as it readily may be, two or three times per second, each set of instruments will be placed in communication with the line 70 twenty-four or thirty-six times in every second, and the circuit will be practically unbroken. The line may therefore be used either for the transmission of messages telegraphically or for any other purpose to which such an arrangement is applicable. 75

The speed of rotation of the apparatus is regulated by adjusting the motor-magnet *F* to or from the armature-disk. The closer the magnet is brought the more powerful is its action 80 on the disk and the higher the speed of rotation. Thirty breaks are shown in the circuit-breaking wheel and thirty teeth on the armature-disk, and the break-wheel is of course so fixed relatively to the teeth that the magnetizing and demagnetizing of the magnet are timed to attract and release the teeth at the proper moment and maintain its continuous rotation. 85

In order to insure the synchronous movement of the apparatus at the two stations, I make use of the following arrangement: At station *X* three of the 9's most widely separated from each other are connected together and to a correcting-battery, *C B*. The other 95 three intermediate 9's are thrown out or unconnected. At the other station, *Y*, the 9's corresponding with those connected with the battery *C B* at station *X* are thrown out, and the other 9's corresponding with those unconnected at station *X* are connected with the correcting-battery *C B'*. At station *X* three 10's most widely separated are connected to each other and to a line which passes through the coils *E E* of the regulating or correcting magnet to the ground, while the remaining alternate 10's are unconnected. At station *Y* the arrangement is again reversed, those 10's corresponding with the unconnected 10's at station *X* being connected together and to a 100 line which passes through the coils *E E* of the regulating-magnets, while the 10's corresponding with the connected 10's at station *X* are thrown out. At both stations it will be observed that the connected 10's are built out or 105 extended toward the adjoining 9's. 110

As described in connection with Figs. 1 and 2, the magnet *E E* can be adjusted both to and from the teeth of the armature-disk and sidewise concentrically therewith, to act in 115 conjunction with the motor-magnet to increase the speed of rotation of the disk.

When the trailing finger or circuit-completer at station *X* is on a battery-connected 9, if the tongue at *Y* happens to be running a trifle faster 125 and touches the edge of an extended 10 at that station, a current of electricity will be received from the battery *C B* at station *X* through the 9-contact and trailing finger at that station over the main line, trailing finger, and 130 10-contact at station *Y* through the coils of the correcting-magnet *E E*. Each correcting-magnet, when adjusted for retarding, is placed relatively to the magnet *F* and armature-teeth,

as shown in the drawings—that is, when two armature-teeth are directly opposite the poles of the motor-magnet F and the motor-circuit is just being broken, as appears from the circuit-breaking wheel, two teeth on the opposite side of the disk have almost passed from in front of the poles of the correcting-magnet E. If, therefore, the correcting-magnet is energized at this moment, it will momentarily attract the teeth just passing from its poles and retard the speed of rotation. When the magnet F is energized and is attracting the two teeth approaching its poles, two opposite teeth come in front of the poles of the correcting-magnet and a correcting-impulse is received. That magnet will momentarily tend to hold these teeth and retard the rotation. The operation is exactly the same at the other station.

As the local motor-circuit at both stations is broken by the break-wheel *g* the same number of times in a single revolution of the trailing fingers with an approximately equal battery-power, the apparatus at the two stations will revolve at about the same speed, and when once brought into synchronism their continuous uniform rotation is automatically maintained by the reciprocal correcting-impulses of electricity transmitted from both stations, according as the apparatus at one station runs faster than that at the other. By shifting the magnet E they may of course be arranged to operate in conjunction with the motor-magnets to accelerate the speed when an electrical impulse is received. The correcting 9 and 10 contacts must, however, be arranged for acceleration. This can readily be done by reversing their relative battery and correcting-magnet connections and extending the 9's toward the 10's, instead of the 10's toward the 9's.

The specific arrangement of the correcting 9's and 10's at each station forms the subject-matter of another application filed simultaneously herewith, numbered 91,489.

As above remarked, in several applications for patents filed simultaneously herewith, and respectively numbered 91,490 and 91,491, I have shown other arrangements of contacts for automatically correcting the motion of rotary apparatus controlled by an automatic vibrator. Obviously, the non-vibratory circuit-breaking apparatus herein set forth may be used in connection with the systems of operation set forth in those applications.

In Fig. 2 an organization is shown like that in Fig. 1, except that, instead of employing a separate magnet for the retarding or accelerating correcting-impulses, the correcting-coils E are mounted upon the same cores as the motor-coils F, so that the effect of correcting electrical impulses which prolong the magnetism of those cores is to hold the armature-teeth in front of them and retard the rotation of the armature-disk.

The right to hereafter file other applications for any subject-matter herein shown or described and not fully claimed is reserved.

Any subjects-matter herein shown or described, but claimed in cases 91,488, 91,489, 91,490, 91,491, or 91,493, filed of even date 70 herewith, or No. 102,928, filed August 6, 1883, are disclaimed herein.

I claim as my invention—

1. The combination, substantially as set forth, of a main line, stations connected therewith, electrically-actuated apparatus and its local circuit at each station for making and breaking the line-circuit, a non-vibratory circuit-breaker at each station for interrupting said local circuit, and means for correcting 80 the speed of said circuit-breakers by correcting-impulses of electricity received over the main line.

2. The combination, substantially as set forth, of a main line, continuously-actuated 85 apparatus for making and breaking the line-circuit through a series of contacts, electrical mechanism and its local circuit for actuating such apparatus, a non-vibratory circuit-breaker for interrupting said local circuit, 90 and means for automatically correcting the speed of said circuit-breaker by impulses of electricity received over the main line.

3. The combination, substantially as set forth, of a main line, continuously electrically 95 actuated apparatus connected therewith for making and breaking the main-line circuit, electric mechanism for actuating such apparatus, a non-vibratory circuit-breaker which controls the speed of said electric actuating 100 mechanism, mechanism for operating said circuit-breaker, and means for correcting the speed of said circuit-breaker by impulses of electricity received over the main line.

4. The combination, substantially as set 105 forth, of a motor-circuit, a battery and magnet, a rotating armature-disk, a trailing finger or circuit-completer, and a rotary circuit-breaker actuated by the rotation of the disk for interrupting the motor-circuit.

5. The combination, substantially as set forth, of a motor-circuit, battery and magnet, a rotating armature-disk, a trailing finger or circuit-completer, a stationary table of insulated contact-pieces, over which the circuit-completer traverses, and a rotary circuit-breaker actuated by the armature-disk for automatically interrupting the motor-circuit.

6. The combination, substantially as set forth, of a motor-circuit, battery and magnet, 120 a rotating armature-disk, a trailing finger or circuit-completer, a stationary table of insulated contacts, over which the circuit-completer travels, a rotary circuit-breaker actuated by the rotating armature-disk for automatically 125 interrupting the motor-circuit, a correcting-battery, to which some of the contacts on the stationary table are connected, and magnetic correcting-coils acting on the armature-disk, connected with other contacts on the stationary table.

7. The combination, substantially as set forth, of two electrically-connected stations, independently electrically rotated apparatus

- at each station, the motor-circuits, circuit-breakers actuated by the rotary apparatus for automatically interrupting the motor-circuits, the tables of contacts, the circuit-completers 5 which traverse the tables of contacts, and mechanism, substantially such as described, for automatically maintaining the synchronous movement of the apparatus by acting on the circuit-breakers.
10. 8. The combination, substantially as set forth, of two electrically-connected stations, the motor-circuits, magnets and batteries, the rotating armature-disks, the trailing fingers or circuit-completers actuated by the armature-disks, the tables of contacts, rotary circuit-breakers for automatically interrupting the motor-circuits, a correcting-battery at each station connected to some of the contacts, and 15 correcting-coils at each station connected to other of the contacts.
9. The combination, substantially as set forth, of the trailing finger, the table of contacts, the motor-magnets, the rotating armature-disk, the break-wheel mounted on the shaft 20 of the disk, the contact-fingers, and means for adjusting the motor-magnet to or from the armature-disk to vary the speed of rotation.
10. The combination, with the rotary armature-disk, of the line, the correcting-magnet, 25 and means for adjusting it to and from the disk and sidewise relatively thereto, to vary the effect of the correcting-impulses received from the line.
11. The combination, substantially as set 30 forth, of a main line, the independently-actuated armature-disk, means for actuating it, and the independent correcting-coil, which acts directly upon the armature-disk to correct its speed of rotation, independently of the 35 actuating devices, when a correcting-impulse of electricity is received from the main line.
12. The combination, substantially as set forth, of a toothed armature-disk, a motor circuit and magnet for driving it, and the independent correcting-coil, which acts directly 45 upon the armature-disk to correct its speed of rotation independently of the motor devices.
13. The combination, substantially as set forth, of a motor-circuit, battery and magnet, an armature-disk, a table of contacts, the circuit-completer actuated by the armature-disk, and a correcting-magnet which acts directly 50 upon the armature-disk.
14. The combination, substantially as set forth, of electrically-connected stations, motor-circuits, magnets and batteries, armature-disks, tables of contacts traversing circuit-completers, circuit-breakers for automatically interrupting the motor-circuits, a correcting-battery at each station connected with 55 some of the contacts on the table, and a correcting-magnet at each station connected with other of the contacts, and acting directly on the armature-disk to regulate the speed.
15. The combination, substantially as set 60 forth, at electrically-connected stations, of mechanism at each station for successively completing and breaking the line-circuit, apparatus for continuously actuating such mechanism, means for automatically sending correcting-impulses of electricity from one station to the other, and a coil which acts electro-magnetically directly on the driven mechanism, which successively makes and breaks the main-line circuit.
- In testimony whereof I have hereunto subscribed my name this 3d day of April, A. D. 1883.
- 75
